Donald Rossie

Serial No. 364 9666X

The schedule referred to in this Letter Patent and making part of the same containing a description in the words of the said Donald Rossie himself of his improvement in the machine for making Butts and Hinges.

I, Donald Rossie, a citizen of the United States, residing in the City of Troy in the County of Rensselaer and State of New York, have invented a new and useful machine for making butts & hinges & that the following is a full and exact description thereof. The improvement is to be applied to the manufacturing of butts & hinges of malleable and ductile metal, the two plates which form the butt or hinge being to be prepared separately in the ordinary practice of making butts of like descriptions each with projections from one edge, no tongue corresponding to this place between the tongues of the other plate, with which they are to be battened. These tongues turned over or bent ^{over} back form what are called the eyes of the hinge, and when placed together, the eyes of each plate between those of the other, as will be seen at the corresponding parts of the hinge. The machine has to be constructed for forming the tongues of the hinge plates from the straight and cylindric pieces. They are in when this space and forming them into eyes, which is to be performed in a block of steel or other suitable material to be provided for this purpose. This is to consist of an opening of the thickness of the hinge plates for which it is designed, extending into the body of the block a distance equal to about the length of the plate with respect to the tongue cylindric, and then to be divided in a circular or longitudinal on one side of the inner wall for forming the eye and from the outside surface of the eye of the tongue, so that the space of the opening within its circumference and the distance between the plates will be the same as the angle

of a fulcrum and sides of the bridge plate of the eye is formed. The whole of this opening is to be extended straight the entire length of the block. This constitutes the eye. And the eyes of the bridge are formed by placing the plate with the tongues extended within the groove or at its mouth and forcing the tongue out forward to the circular termination of it. The effect of which will be that as the tongue cuts the circle in the middle division of a tangent line passing through the ends are forced round its surface, which for this purpose should be smooth, till the tongue is conformed to the curve, having bent flatwise in some little length, or so as to bring the ends even to the same surface or to that of the plate to which they belong. The effect of this operation is that following a deposit to the groove and the end of it to the edge of the bridge plate should be provided and a receding movement given to it sufficient to extend and force the tongue, the tongue especially, into the block and then to return back far enough to allow the bridge plate to be removed and another placed before the following ready for a like operation. This may be done by fixing the block firmly upon a frame to be provided for the purpose, and causing a staff or with a comb or a pointed section to impinge before it, with a piston or shuttle bar connected therewith and extended to and connected with the piston by a flexible joint - such as is ordinarily applied to operations of that kind - and gives the piston a moving force. As both these means of power are now commonly used for producing movement of like nature, no detail need be given of methods for applying either of these powers, as by means of casting or otherwise may be adopted in this case as shall be necessary and convenient. The piston may be supported and kept true in its operation by means of projections, or wings, so as by casting from a horizontal and circular bar the tongue and groove or the block with the sides of the same produced for the purpose.

A larger lever extending along on one side of the frame from near
 the shaft to a point opposite the end of the die, may be so con-
 nected with the machinery, as to have a lateral movement outwards
 and inwards to the said shaft, so that the shaft by means of a comb upon
 the side of the die, will drive the shaft or of a dash or pulley
 connected with the revolving work, so that by suspending or attach-
 ing it by a movable joint to a part of the frame provided
 for the purpose, as the fulcrum, at such point between the two
 sides taken, as shall be convenient, the said lever operating
 will draw the said shaft, so as to oppose the die, and
 by attaching a follower shield, so as to move backwards and forwards
 in the direction of the length of the die, it may be made to run
 round it and receive the long plates after they are pro-
 cessed, by passing it out at the opposite end. The relative
 position of the comb and the said shield, so that the latter is in contact
 with the end of the former, may be such as to cause the
 said shield, to turn outwards, so as to bring the two followers, before it
 towards each other, so that when the first is having
 a lever from the die, and preparing, to its return with
 another long plate, before it, the said follower will pass
 in contact with the said plate, which is finished. To also the eye
 of the end of the said follower may be adapted to such
 a purpose, by the action of the followers of the lever as is pre-
 paring the next one and so on. When this is done, the comb will
 bring the lever to the end of the combing, again. Instead
 of lever for the above purpose, the same effect may be produced
 by means of a shaft, along the end of the frame, to be connected
 by gear with the revolving shaft in front of the die, and
 working as a sort of a vertical section, opposite the end of the die
 and before the rear end in the form of a ^{right} angle, the said
 gear, connecting, a follower, so as to oppose the said comb
 in order to accelerate the return of the said follower after being

that carried with the dice by the motion of the lever or of the casting
upon the lateral shaft, or spring may be attached to a hinge
of the frame and be applied to the lever or an appendage of it in such
a manner as to cause appendage of the following to the others as to replace
the following, as its outward position. The instant the operating
wheel shall have passed the point of its ultimate action for propelling
of persons, the wheel for the purpose should be forced with a con-
tinuous effort, so that as abrupt to admit of such rotation.
This provision is for the purpose of propelling every other passenger between
the following or bridge plates. Within the die, which is already
referred to in this particular, might occasions, as when the
descriptions of this provision rather than of the Specie or Minima
are applied, the result is to be rendered oblique its frontal
application as left as a means of direct use to be exercised
in the construction of this part of the apparatus. By placing
a bridge plate on purpose for the die, before the said passenger
with the bridge as situated in the right direction, the
same may be carried in by its sideways and placed in
the groove before the other passenger ready to be forced into its
groove. The plate thus supplied may be made to stand
before it, that it may be furnished with a means of entering the die
when so. That may be done as prepare the passenger for the nature of
the other passenger. Upon this principle an engine might be built
using the greatest and greatest as a stopper before the next passenger
enters. Moreover, that, as a means of carrying of bridge plates
using the place one again another, and so on, with the longue
and narrow direction, and the following will be most in demand
that die be made to drag before it, so that the groove of the said
bridge plate can be introduced and drawn back to the
end of the bridge, so as of the bridge plates within it, the may
be used for carrying of bridge plates and to be used for
the same purpose. If the passenger is to be made to stand for so
long time, as to break a passage open between the following and

and the die sufficient for the lower plates to be raised through
the distance above will be kept in place by the sides of the dies
until the following process is taken back from under them.

Position of this location for the upper die may be fixed
in front of the other before the other follows so as to have the
lower hinge carried dry, & directly into the die with the
topges and foretops. While the end follows may as
before be applied to the removing of the plates from the die
when finished. Instead of a die of the foregoing description
one may be made to answer the same purpose by having a
die horizontal, with dies parts — the division consisting
as or near the back part of the circular termination of
the groove and continuing through to the back side of the block
of the two pieces which in this case would be substituted for
it. In every other respect the die should be the same as that
above described. In order to keep them firmly together during
the process of passing the eyes of the hinge plates will be re-
sist the pressure which that state occasions, an expedite
method would be placed over the die extending across the
joints and secured by journals in pits holes provided there
at the sides so that by turning the projecting side of the outer
cover before the upper part of the die, it will give passage to it
and prevent the plates from the die as if it were constituted of one
large block, and by turning the latter back after the eyes are
passed it will release the plates from the pressure to which
they will be subjected by the process and cause an
immediate separation, even had the pressure of the
upper plates been. By this improvement this process
will speedily be described. It claims as my own invention
the manner and principles of turning or bending the topges
hinge or butt plates of malleable as malleable metal and
removing them with eyes by forcing them into a die constructed
for that purpose. It also claims the malleation

as above described, and the principles thereby embodied and every part thereof as above combined, and as constituting a whole and as specially applicable to the above purpose of bending the tongue and forming the eye of hawks, and to the several processes therewith connected.
